PROCESS OF TREATING GREASE WOOL

Rudolph James Wig, San Marino, Calif., assignor
to California Process Company, Los Angeles,
Calif., a corporation of Nevada

Application August 24, 1936, Serial No. 97,671

7 Claims. (Cl. 19—66)

This invention is a novel improvement in the treatment of so-called grease wool, pulled wool, and unscoured wool; and the principal object of the invention is to avoid the present necessity for 5 scouring such wools before they can be carded. In the following description and claims I use the term "grease wool" as including the aforementioned wools, and also the greasy "waste" wools obtained in the manufacture of woolens and 10 worsteds.

In all commercial processes of treating grease wools it has been necessary to wash or scour the wool before carding it, because the wool contains or retains so much grease or oil that if it is attempted to card it the grease adheres to the card wires and soon renders the card useless thereby 15 occasioning much delay and expense, and materially lessening the efficiency of the carding machines.

The washing or scouring of the raw wool prior 20 to carding results in considerable entangling or felting of the wool fibres; and the tearing apart in the carding machines of the tufts or entangled fibres causes much breakage of the fibres with 25 consequent lessening of their value; as long fibres are most desirable. Another objectionable result of washing or scouring of grease wools prior to carding is "nibbing" of the fibres; that is, in the 30 scouring process the ends of some fibres are doubled up or rolled into "nibs" which cause unevenness in the finished yarn or wool tops.

My invention avoids all the disadvantages of 35 preliminary washing or scouring of grease wools; and enables such wools to be opened and carded prior to washing; and further enables the washing operation, if desired, to be performed on the 40 wool after it has been carded and while in the form of a "sliver" or bat.

The standard woolen and worsted carding machines deliver the carded wool in the form of a bat, which is condensed into a continuous "rope", commonly referred to in the industry as a "card sliver", or a "roping".

In my process before carding the grease wool 45 is subjected to a low temperature sufficient to freeze the grease on the wool, without injuring the fibres; a temperature as low as 15° F. to 60° F. below zero may be used, although higher temperatures will suffice on some wools. While in 50 such frozen condition the wool is carded. Preferably the wool is opened up by a beater or duster either before or after refrigeration, but it must be carded while in a frozen condition, and the carding machine also maintained at such a low 55 temperature that the grease on the wool will not

be so warmed thereby as to tend to stick to the cards.

In this specification where the term "wool" is used, I mean to include wool or animal fibres and other fibres which contain extraneous grease or oil and can be subjected to low temperatures sufficient to freeze the extraneous grease or oil without rendering the fibres so brittle or stiff as would cause breakage thereof if combed, etc., while at low temperature. Further, by the expressions "frozen wool" or "freezing the wool" I mean that the wool or other fibres have been or are exposed to a temperature sufficiently low to freeze the extraneous grease or oil upon the fibres; but the fibres retain sufficient flexibility so that there is no appreciable breakage of the fibres when 10 combed, etc., at low temperature.

When grease wool is exposed to freezing temperature, the grease becomes brittle. If in this state the grease wool is passed through an opener, the tufts of wool are spread apart sufficiently 20 and the fibres released from the glued effect of the grease so that it can be fed on to a card and carded before it becomes materially entangled.

Preferably I would place the carding machine in the chamber containing the refrigerating and 25 opening or dusting apparatus, or at least in a room which is kept at sufficiently low temperature to keep the wool and machine in a refrigerated condition; and introduce the frozen wool (without exposing it to normal atmosphere) directly from the opener or duster to the carding machine, and thus card the wool while in a refrigerated condition. From the refrigerated carding machine the wool is discharged in a continuous 30 sliver or bat; and the cleaned and carded wool in the form of such sliver or bat can be most efficiently and economically washed to remove the 35 small amount of grease and dirt remaining in the wool without producing the undesirable entanglement or felting and nibbing of fibres that occurs 40 when loose grease wool is scoured as above mentioned.

It is cheaper to wash the wool in the form of a 45 sliver than when in loose condition. After the fibres are thoroughly separated on the card, the batting in the form of a sliver may, either before or after gilling, be washed with a much less resultant felting and entanglement of the fibres.

The wool sliver or bat can be readily washed in 50 the so-called "backwasher" machines used by the worsted industry for removing oil and dirt (which has accumulated in carding) from the card sliver after it has been gilled and before combing. While it is common practice to backwash the card 55

sliver either before or after gilling; if it is desired to do the backwashing after gilling, it may be preferable to have the gill box arranged in the refrigerated chamber.

5 With some wools it might also be desirable to do the combing in the refrigerated chamber, in which case the combing machine could also be placed in such chamber.

10 The wool may be retained in a refrigerated state from the time it enters the chamber as a grease wool until all the operations thereon have been performed which it is desired to complete before the wool is scoured. After the wool is discharged from the refrigerated chamber, it may 15 be desirable to wash it before any subsequent operations are performed upon it.

15 In my process as stated after carding the frozen grease wool the wool may be washed, or may be gilled and combed before it is washed. In my 20 process all the steps such as opening, carding, gilling, and combing may be performed while the wool is in a refrigerated condition, or at such a temperature that wool containing grease does not cause trouble in the carding, or gilling, 25 or combing machines. The freezing may be accomplished in one compartment or chamber, and the carding in another refrigerated compartment or chamber; or the carding machine may be in the same chamber as the refrigerating apparatus. If desired the gilling and combing machines may be similarly located in the same or different refrigerating chamber; or located in the refrigerating chamber with the carding machine. The arrangement of the machines may 30 vary according to the work desired to be performed on the wool prior to spinning it into yarn or prior to washing the so treated wool.

35 While the process is especially designed and adapted for the treatment of grease wool, it may 40 be also used for the treatment of other fibrous materials containing such amount of grease, wax or oils as would interfere with the carding thereof under normal atmospheric conditions, and which material would not be injuriously affected 45 by the low temperature employed.

45 In the accompanying drawing I have illustrated diagrammatically some of the variations of treatment of grease wools in accordance with my invention.

50 In the diagram, Fig. 1, grease wool is passed through a refrigerating means, an opener and a carding machine all contained in a refrigerated chamber, so that the wool is frozen and then opened and carded in its frozen condition, and 55 before it is discharged from such chamber. After it is discharged from such chamber the wool can be spun without washing, if it is of the proper quality; or it can be re-carded and spun without washing; or can be gilled, combed, re-gilled 60 and then spun without washing. The various subsequent treatments of the wool after it is discharged from the carding mechanism depends upon the grade of the wool and the use to which it is to be put. If it is desired to wash the wool 65 after the carding, the carded wool in the form of a "sliver" could be washed, re-carded and spun; or washed recarded, gilled, combed, regilled and spun; or washed, gilled and spun; or washed, 70 gilled, combed, re-gilled and spun.

75 After "opening" the wool might also be cleaned or screened in the refrigerating chamber before carding it; such opening and cleaning could be performed by a single machine such as described in the Brown Patent #1,894,154.

75 If desired, as indicated in Fig. 2, the freezing

and opening; or freezing, opening and cleaning; might be performed on the wool in the refrigerated chamber; and then the wool discharged therefrom and stored; and when it is desired to card the wool the stored opened and cleaned 5 wool could be re-frozen and then carded. After such carding the wool may be treated in any of the several ways hereinabove stated as following the carding in the arrangement shown in Fig. 1.

10 As shown in Fig. 3, the grease wool before being frozen may be opened up by any suitable mechanism and then admitted into the refrigerating chamber and frozen; and then passed to a carding machine within the refrigerating chamber; then the carded wool can be subjected 15 to further treatment in any of the ways above described with reference to Figs. 1 and 2.

15 As indicated in Fig. 4, the freezing apparatus, the opener, the card and gill, may be all placed in one refrigerated chamber, and the several 20 operations successively performed upon the wool while in frozen condition in such chamber. The gilled wool discharged from this chamber may then be combed, re-gilled and spun; or may be re-gilled, combed, again gilled, then spun, according to the use to which the wool is to be placed. If desired the gilled wool discharged from the refrigerating chamber may be washed before re-gilling, and then treated as above described with reference to Figs. 1-3.

25 As shown in Fig. 5, the freezing, opening, carding, gilling, combing and re-gilling mechanisms may all be contained in one refrigerated chamber. The re-gilled wool can be discharged from the chamber and taken to the spinner; or if desired such re-gilled wool may be washed, again 30 gilled and then spun. Other variations may be used; but in each case it is essential that the wool be carded while in a frozen condition.

35 In my process if cleaning is desired I preferably refrigerate and clean the grease wools by apparatus described in the aforesaid Brown patent but the small percentage of grease remaining in the cleaned wool will cause trouble in the carding machine as it melts and fouls the cards 40 when such wool is run without washing it through the carding machines in the ordinary manner at ordinary room temperatures; and my invention will prevent and obviate any possibility of such trouble.

45 The opener, card, gill and comb may be located in the same room or in different rooms, although it would be preferable to keep the wool in a frozen condition until all these operations have been completed, unless the wool is washed before the 50 gilling or combing operation.

55 The carding operation in the worsted process is for the purpose of fiberizing or separating the individual fibres from one another, so that they can be drawn apart with the least possible entanglement. The fibres are not delivered from the card parallel to one another in the ordinary carding operation. While the fibres may be somewhat parallel during the carding processing, as the bat is delivered from the card in the 60 form of a sliver, much of the paralleling has been destroyed, and the fibres may assume different relative positions in the bat. The gilling operation is one in which the card sliver is passed through a series of combs, these combs tending 65 to parallel the fibres. Therefore it is customary to pass the card sliver through several gill boxes before combing. In the combing operation, the long fibres are separated from the short fibres 70 which are known as "noil".

If the wool is to be used in the manufacture of woolens, it need not be gilled, or combed; therefore, it can either be fabricated directly into roping by the carding machines in the refrigerating chamber; or discharged from such chamber as a sliver or bat and formed into roping on another carding machine at normal temperature, either before or after washing.

My process is applicable to any grease wool or animal fibres whether or not it contains vegetable or other foreign matter. Such wool or fibres may be frozen by any suitable means, opened by passing through some standard type of opener and then fed, through a standard wool feeder without such exposure to atmospheric air as would soften the grease, into a woolen or worsted card; the opener, feeder and card all being in a refrigerated chamber or chambers.

I claim:-

1. The process of treating wool, consisting in subjecting the wool to a temperature that will refrigerate the wool and congeal the grease on the fibres, and thereafter subjecting the wool to a carding operation while the wool is in a refrigerated condition with the grease congealed thereon.

2. In the process as set forth in claim 1, the freezing and carding operations being performed in a refrigerated chamber.

3. The process of treating wool, consisting in subjecting the wool to a temperature that will refrigerate the wool and congeal the extraneous grease on the fibres, opening such wool while in refrigerated condition, storing the wool, and

thereafter again refrigerating the wool and carding it while in a refrigerated condition.

4. The process of treating wool consisting in subjecting the wool to a temperature which will refrigerate the wool and congeal the grease on the fibres, opening and cleaning such wool, and thereafter subjecting the wool to a carding operation while the wool is in a refrigerated condition with the grease congealed thereon.

5. The process of treating wool, consisting in subjecting the wool to a temperature that will refrigerate the wool and congeal the extraneous grease on the fibres, opening and cleaning such wool while in such refrigerated condition, storing the cleaned wool and thereafter again refrigerating the cleaned wool and carding it while in refrigerated condition.

6. The process of treating wool, consisting in subjecting the wool to a temperature that will refrigerate the wool and congeal the grease on the fibres, and thereafter subjecting the wool to a carding operation and to a gilling operation while the wool is in a refrigerated condition with the grease congealed thereon.

7. The process of treating wool, consisting in subjecting the wool to a temperature that will refrigerate the wool and congeal the grease on the fibres, and thereafter subjecting the wool to a carding operation, to a gilling operation and to a combing operation while the wool is in a refrigerated condition with the grease congealed thereon.

RUDOLPH JAMES WIG.
